UNITED STATES PATENT OFFICE.

CHARLES S. SWEET, OF HUBBARD WOODS, ILLINOIS.

SLEEPING-CAR BERTH.

Application filed March 31, 1923. Serial No. 628,983.

My invention relates to sleeping cars and is designed to make the upper berths thereof easily accessible and to provide individual dressing space and additional storage space.

It is desired to produce an improved upper berth and means of access thereto and dressing space in connection therewith so that the upper berth may become as desirable, if not more so, than a lower berth, by providing a series of stationary and permanent steps and a platform leading to the upper berth so that the occupant may easily ascend or descend, and may be able to dress or undress in privacy from a standing position with sufficient head room and means of enclosing such steps and platform during the daytime in order to eliminate the danger to public life and limb on account of falling on such steps and platform, especially when the car is in motion; and at the same time to maintain the present day interior beauty of sleeping cars. It is a well recognized fact that upper berths are not considered by the public as desirable as lower berths because of the difficulties above specified and which my invention is designed to overcome.

The invention resides in the accomplishments of the above objects by providing a space between the backs of adjacent seats sufficiently wide to permit a person to pass therebetween. The steps and platform are mounted within said space for easy approach to the upper berth which remains at the present standard height and width. The utilization of my invention will result in approximately the loss of two lower and two upper berths in the present standard twelve section drawing room car, but it is contemplated that with the increased desirability of the upper berth in a car embodying this invention which will have greater head room and space for hanging clothes than is now available in lower berths, an increase over the present charge for upper berths can be made, or a greater use of the upper berth to more than offset the loss of berth space. Further objects, advantages and capabilities will become apparent as the specification proceeds.

My invention further resides in the novel construction, combination and arrangement of parts illustrated in the accompanying drawings, and while I have shown therein a preferred embodiment, I desire it to be understood that the same is to be considered as illustrative only, and not as limiting my invention, while my claims refer for the most

part to a lower and upper berth it is understood to be applicable also to a room in a sleeping car, an enclosed section of lower and upper berth, or a plurality of these, and with the areaway or compartment adjacent the ends or sides of the berths as desired.

Referring to the drawings:—

Fig. 1 is a vertical transverse sectional view of a portion of a sleeping car with the upper berth in closed position.

Fig. 2, is a similar view in open position.

Fig. 3, shows a sleeping car section in perspective.

Fig. 4, shows a modification of the sustaining means of the upper berth.

In the drawings, Fig. 3 represents a section of a sleeping car embodying my invention with the berths made up ready for occupancy. I have interposed a space between the back portions of the seats of some 16 inches in width which in the day time when the berths are not in use, is covered by a side panel 1 and a top panel 2. At night when the berths are made up, the side panel is removed and placed under the seat or otherwise disposed of, or it may be hung as a door on hinges and may be pushed into the areaway or compartment and out of the way. The top panel 2 is placed in position between one of the seats and the upper berth 3 as shown in Fig. 3, and thus serves as a headboard to afford privacy to the lower berth, in this position it may also be used as a means for sustaining the end of the upper berth adjacent the areaway or the compartment when the upper berth is lowered for occupancy.

When the car is made up for occupancy at night and the panels 1 and 2 are adjusted, the space afforded within the pair of adjacent seats provides an areaway for communicating with the upper berth. A permanent horizontal step 4 extends rearwardly from the aisle and at sufficient height to afford easy ascending or descending. Platform 5 is elevated above said step and provides standing space while the occupant of the upper berth is dressing and the additional step 6 is provided by mounting a single flat support of metal or wood between the backs of the seats or to the side walls of the car. This flange like step affords an easy step for mounting into the upper berth, but does not interfere with the placing of luggage of considerable length on the platform 5. A movable grab handle 7 is rotatably mounted on the back of one of the seats and at night after the upper

berth is lowered, is swung into vertical position, where it has locking engagement into a holder 8 secured to the upper berth 3. When in holding position it not only serves as a grab handle for passengers, but helps to sustain the weight of the upper berth. An additional grab handle 9 is mounted on the opposite side for the convenience of the occupant of the upper berth. The separate movable partition 14' when in position enables the areaway and berth section to be separated from other berths.

The ordinary upper berth is raised and lowered by means of pulleys 10 and chains 11, and in the present construction of sleeping cars the chains extend from each of the front ends of the upper berth back to pulleys fastened to the side car walls of the car at about the same height from the car roof as the front side of the upper berth when in closed position.

My invention contemplates either an upper berth with a resistance spring pulley and chain at one end only of the upper berth and opposite the steps so as not to interfere with ingress or egress of the occupant, or if it is desired to use a chain and pulley at both ends, said chain in the modified construction may slide along a groove fitted on the upper edge of the end of the upper berth adjacent the entry way. When the upper berth has been lowered, the chain 11 may be pushed back to the side wall of the car within the groove and will thus be out of the way of the occupant as he enters the berth. Attached to the end of the chain is a roller rod or wheel, (not shown in the drawings) which slides within the slot and is held at the front or aisle side position by elevations 12. To detach the chain from the elevation 12, it is necessary to pull the chain down until it is out of locking engagement with said elevation or hump and then push it to the back or the car wall side of the upper berth, where it is held in a similar elevation as shown in Fig. 4. In closing the upper berth, the force of gravity will disengage the chain from the rear hump and it will travel forwardly along the slot 13. From the foregoing description it will be seen that at night when the lower and upper berths are made up as beds in a car embodying this invention, the occupant in the upper berth can easily and quickly ascend to the upper berth without danger of falling and without the use of ladders, and when standing on the platform can comfortably dress or undress while standing in upright position. Ample space is also thus afforded for hanging up clothes.

A movable curtain or partition 14, is provided to be used when the berths are made up for sleeping purposes to enclose the front or aisle side of the upper and lower berth and the areaway. The curtains are suspended from a movable rod paralleling the front or

aisle side of the upper berth at a convenient height above the level of the upper berth when lowered.

It is, of course, understood that, while I have shown and described what I now consider a preferred form of my invention, the specific description of structure set forth above may be changed without departing from the spirit of my invention as set forth in this specification and the appended claims.

Having now described my invention,

I claim:

1. In a sleeping car a plurality of sections consisting of a lower berth and an upper berth, a chain at each end of said upper berth to sustain and to facilitate raising and lowering of said upper berth, a resistance spring pulley for cooperation with said chain, a slotted groove at the top edge of the end of said upper berth and an enlargement at the lower end of said chain engaging said slotted groove and having sliding engagement therein.

2. In a sleeping car, a plurality of sections of lower and upper berths endwise adjacent each other, a compartment between said sections, and permanent steps within said compartment, supporting means for one of said upper berths adjacent said compartment and having movable attachments to said upper berth so that it can be moved to such position when the berth is lowered as to permit the occupant free and unobstructed passage between the compartment and the upper berth.

3. In a sleeping car, a plurality of sections of lower and upper berths endwise adjacent each other, a compartment between said berths and means therein for access to one upper berth only, auxiliary supporting means for said upper berth adjacent said compartment and having a movable attachment to the upper side of said upper berth so that it can be moved to such position when the berth is lowered as to permit the occupant free and unobstructed passage between the compartment and the upper berth.

4. In a sleeping car a plurality of sections of lower and upper berths endwise adjacent each other, an areaway between said sections, means in said areaway for easy access to the end of the upper berth adjacent to said areaway, means of supporting said upper berth at the end adjacent said areaway when said upper berth is in lowered position, adjustable means to permit ready access from said areaway to said upper berth of said section, means for segregating said upper and lower berths and areaway from rest of said car with partitions, and means to enable the segregation of said upper berth and said areaway from said lower berth and from the rest of said car.

5. In a sleeping car, a plurality of sections, on each side of the car, an aisle separating each plurality of sections, each section having a lower berth, and upper berth, an area-

way adjacent one end of the lower berth, permanent steps within said areaway for access endwise of said upper berth, a dressing platform within said areaway at such a height to afford standing room between it and the car roof, and means for opening and closing said areaway when desired.

6. In a sleeping car, a plurality of enclosed sections, each section having a lower berth, an upper berth and an enclosure providing an areaway adjacent one end of the lower berth, means for access to said enclosed lower and upper berths when desired, permanent steps within said areaway for access endwise of said upper berth, a dressing platform within said areaway at such height to afford standing room between it and the car roof, and means for opening and closing said areaway when desired.

7. In a sleeping car, a plurality of sections, each section having a lower berth, an upper berth, an areaway adjacent one end of the lower berth, fixed means within said areaway for access endwise of said upper berth, a dressing platform within said areaway at such a height to afford standing room between it and the car roof, and partitions segregating said areaway and said upper berth from the rest of said car, and means for closing the areaway when said upper berth is not in use.

8. In a sleeping car having lower and upper berths, an areaway paralleling and adjacent one end of the lower berth, means within said areaway for mounting to said upper berth, a dressing platform within said areaway at such height to afford standing room between it and the car roof, means for closing the open top and side of said areaway when said upper berth is not in use and to partially segregate and enclose said areaway and said upper berth from the other berths when said upper berth is in use, grab handles, one of which at least being rotatably mounted at one end and detachably connected at the other, said grab handle supporting front end of upper berth adjacent to said areaway when said berth is in lowered position, and sustaining means to hold said upper berth in lowered position and to facilitate raising and lowering of said upper berth.

9. In a sleeping car having lower and upper berths, an areaway paralleling and adjacent one side of the lower berths, means within said areaway for mounting to said upper berth, a dressing platform within said areaway at such height to afford standing room between it and the car roof, a removable end panel and top panel, enclosing said areaway when not in use, said removable side panel and a separate movable partition segregating said areaway and said upper berth, when in use, from the other berths, grab handles to assist in mounting to said upper berth, curtains detachably connected to enclose and

segregate the upper and lower berths and areaway from those adjacent thereto.

10. In a sleeping compartment having lower and upper berths, fixed means endwise adjacent the lower berth for access to the upper berth, a sustaining chain for said upper berth, a resistance spring pulley for cooperation with said chain, one end of said chain being detachably connected to a lower rod or wheel, a slotted groove at the top edge of the end of said upper berth adjacent to said fixed means, to receive said roller rod or wheel and permit sliding engagement therein.

11. In a sleeping car, having upper and lower berths, an areaway adjacent one end or one side of the lower berth, means therein for access to said upper berth, a movable top panel to support the end of upper berth adjacent to said areaway when said upper berth is in lowered position and to wholly segregate the lower berth from the areaway and upper berth immediately above said top panel, a movable aisle side panel enclosing said areaway when said upper berth is not in use, and partitions segregating said areaway and said upper berth from the rest of the said car.

12. In a sleeping car, having upper and lower berths, an areaway adjacent one end or one side of the lower berth, fixed means within said areaway for access endwise or sidewise as the case may be of said upper berth, a dressing platform permanently mounted within said areaway at such a height to afford standing room between it and the car roof, a movable top panel to support the end of upper berth adjacent to said areaway when said upper berth is in lowered position, and to wholly segregate the lower berth from the areaway and upper berth immediately above said lower berth, a movable aisle side panel enclosing said areaway when said upper berth is not in use, and partitions segregating said areaway and said upper berth from the rest of said car.

13. In a sleeping car, having upper and lower berths, an areaway adjacent one end or one side of the lower berth, means within said areaway for access endwise or sidewise as the case may be of said upper berth, a removable end panel and top panel, enclosing said areaway when not in use, one at least of said panels to support the end of the upper berth adjacent to said areaway when said upper berth is in lowered position and to wholly segregate the lower berth from the areaway and upper berth immediately above said lower berth; grab handles, one of which at least being rotatably mounted at one end and detachably connected at the other to assist in mounting to said upper berth, partitions segregating said areaway and said upper berth from the rest of said car.

14. In a sleeping car, having upper and lower berths, an areaway adjacent one end

or one side of the lower berth, means within said areaway for access endwise or sidewise as the case may be of said upper berth, movable panels for closing the open top and side 5 of said areaway when said upper berth is not in use or when said areaway is not in use one at least of said panels and a separate movable partition segregating said areaway and said upper berth, when in use, from the other berths in said car, grab handles to assist in mounting to said upper berth, one of which at least being rotatably mounted at one end and detachably connected at the other, said grab handle supporting the front end of the 15 upper berth adjacent to said areaway when said berth is in lowered position, and curtains detachably connected to enclose and segregate the upper and lower berths and areaway from those adjacent thereto.

15. In a sleeping car, having upper and lower berths, an areaway adjacent one end or one side of the lower berth, means within said areaway for access endwise or sidewise as the case may be of said upper berth, movable panels for closing the open top and side 20 of said areaway when said upper berth is not in use or when said areaway is not in use, one at least of said panels and a separate movable partition segregating said areaway and said upper berth, when in use, from the other berths in said car, grab handles to assist in mounting to said upper berth, one of which at least being rotatably mounted at one end and detachably connected at the other, said grab handle supporting the front end of the 25 upper berth adjacent to said areaway when said berth is in lowered position, a chain at each end of said upper berth to sustain and to facilitate raising and lowering of said 30 upper berth, a resistance spring pulley for co-operation with said chains, one end of the chain at the end of the upper berth adjacent

to said areaway being detachably connected to a lower rod or wheel, a slotted groove at the top edge of the end of said upper berth 45 adjacent to said areaway, to receive said roller rod or wheel and permit sliding engagement therein, and curtains detachably connected to enclose and segregate the upper and lower berths and areaway from those adjacent thereto.

16. In a sleeping car having lower and upper berths, an areaway paralleling and adjacent one side of the lower berths, means within said areaway for mounting to said upper berth, a dressing platform within said areaway at such height to afford standing room between it and the car roof, a movable end panel and movable top panel, enclosing said areaway when not in use, a separate head partition, one or more of said panels and said partition segregating said areaway and said upper berth, when in use, from the other berths, grab handles to assist in mounting to said upper berths, curtains detachably connected to enclose and segregate the upper and lower berths and areaway from those adjacent thereto.

17. In a sleeping car, a plurality of sections, each section having a lower berth and an upper berth, an areaway adjacent and beyond said upper and lower berths, separating said section from other sections, and means of access from the areaway of each section to said upper berth of that section only, a 70 sustaining chain for said upper berth and means for disengaging said chain from sustaining position to permit access to said upper berth when said upper berth is in lowered position.

In witness whereof, I hereunto subscribe my name to this specification.

CHARLES S. SWEET.
